UNITED STATES PATENT OFFICE.

FRANK W. LOWE, OF BOSTON, MASSACHUSETTS.

WINDOW-SHADE FIXTURE.

No. 927,366.

Specification of Letters Patent.

Patented July 6, 1909.

Application filed June 25, 1908. Serial No. 440,253.

To all whom it may concern:

Be it known that I, FRANK W. LOWE, of Boston, county of Suffolk, State of Massachusetts, have invented an Improvement in 5 Window-Shade Fixtures, of which the following is a specification.

This invention particularly relates to outside fixtures for window shade rollers, which comprise a fixture having a bearing in which 10 a projecting shaft on one end of the roller may rotate and a fixture having a vertical slot, open at the upper end, in which the flat, spring-winding shaft is held from rotation.

The object of my invention is to provide a 15 pair of fixtures of the above character, each of which may be made of a continuous piece of wire bent into suitable form. I accomplish this object by the means shown in the accompanying drawing, in which,

20 Figure 1 is a front elevation showing a pair of shade fixtures with the shade roller thereon. Figs. 2 and 3 are side elevations of the two fixtures respectively.

The bearing fixture comprises a continuous 25 piece of wire having a threaded shank a adapted to be screwed into the window casting, the wire being bent at right angles to said shank portion to provide a downwardly extending portion a' , then circularly, to provide 30 a screw-eye a^2 , then upwardly to provide a section a^3 parallel to the section a^2 , and then forwardly at right angles, and in the opposite direction from the shank a , to provide an arm a^4 , said arm being circularly bent 35 at its end in a vertical plane to provide a bearing a^5 adapted to receive the projecting shaft b of the shade roller c . The holding fixture also comprises a continuous piece of wire bent to provide a shank d , threaded, as 40 shown, a depending portion d' , a screw-eye d^2 , a parallel, upwardly extending portion d^3 and a forwardly and horizontally extending arm d^4 , substantially the same as already described, with relation to the other bracket. 45 The end portion, however, of the arm d^4 is extended vertically upward from said arm d^4 , forming a section d^5 , and then obliquely upward, outwardly or away from the other fixture, and then semicircularly and downward 50 in the same plane, forming an inclined loop portion d^6 , and then vertically downward to the arm d^4 , in a direction parallel to the sec-

tion d^5 , forming a section d^7 , which, with the section d^5 forms a vertical slot or recess, adapted to receive the flat-ended spring-winding shaft e of the roller and hold the same from rotation. Screws f are adapted to be passed through the eyes a^2 and d^2 , to hold the fixtures from turning on their shanks after they have been screwed in place, as will be obvious.

In placing the shade roller in position, the shaft b is inserted in the eye a^5 , and then the shaft e is lowered into the slot formed by the sections d^5 and d^7 , the obliquely extending 65 connecting loop d^6 permitting the projecting shaft e to be placed in and removed from said slot.

A fixture made according to this invention, is of inexpensive construction, unobtrusive 70 in appearance, and fulfills all practical requirements.

Having thus described my invention, what I claim as new and desire to secure by Letters Patent is:—

1. A shade roller fixture composed of a continuous piece of wire bent to provide a screw-receiving loop, a supporting shank extending at right angles thereto from one side portion of said loop, and a roller supporting 80 arm extending from the other side portion of said loop oppositely to said shank, said arm having its end portion bent upon itself to provide a roller holding and retaining portion, substantially as described. 85

2. A shade roller fixture comprising a continuous piece of wire bent to provide a vertically disposed screw-receiving loop, a supporting shank extending horizontally from one member of said loop, an arm extending 90 horizontally from the other member of said loop, and oppositely to said shank, said arm having its end portion extended upwardly, then longitudinally toward the shank, and then downwardly to the arm, to form a shaft-holding slot, the upper portion of the loop thus formed extending to one side of the vertical plane of the lower portion thereof, so that said slot will be open at its upper end, substantially as described. 95

3. A shade roller fixture comprising a continuous wire bent to provide a supporting shank, and an arm extending oppositely therefrom, said arm having its

bent upon itself in loop form, the sides of the loop next the arm being parallel to form a shaft holding slot and the other portion of said loop being extended to one side of the 5 plane of said slot-forming sides, substantially as described.

In testimony whereof, I have signed my

name to this specification, in the presence of two subscribing witnesses.

FRANK W. LOWE.
